ORNAMENTAL CHAIN

William F. Hess, Pawtucket, R. I., assignor to
Armbrust Chain Company, a corporation of
Rhode Island

Application March 14, 1938, Serial No. 195,699

4 Claims. (Cl. 59—35)

My present invention relates to the manufacture of jewelry and has particular reference to a novel construction of ornamental band or chain and a novel method of manufacture and assembly.

5 It is the principal object of my invention to provide an ornamental flexible chain which is economical to manufacture and assemble and which will eliminate the use of individual connecting links.

10 Another object of my invention is to provide an ornamental chain, the parts of which can be readily stamped out of sheet metal and assembled into a flexible chain.

15 A further object of my invention is to provide an ornamental wrist chain which will resist normal strains and pulls and which cannot be easily broken or separated.

20 Another object of my invention is to provide an ornamental chain having the aforementioned characteristics which can be ornamented, plated, or colored to present a pleasing appearance to the eye.

25 With the above objects and other advantageous features in view, my invention consists of a novel method of assembly and a novel arrangement of parts, more fully disclosed in the detailed description following in conjunction with the accompanying drawing, and more specifically defined in the claims appended hereto.

30 In the drawing:

Fig. 1 is a plan view of a segment of a chain embodying the present invention;

35 Fig. 2 is a perspective view of a metallic stamping for making one link therefor;

Fig. 3 is a perspective view of a link blank ready for assembly;

Fig. 4 is a perspective view of two links showing the method of joinder, and

40 Fig. 5 is a perspective view of the same links joined, one of the links being completely finished.

45 Referring more in detail to the drawing illustrating my invention, the chain 8 illustrated in Fig. 1 is made of a plurality of separate links 9 hingedly connected together. The numeral 10 generally designates a sheet metal stamping of any suitable metal such as brass for forming a link in the chain in the present invention, 50 the stamping being preferably rectangular in shape and provided with two spaced rectangular slots 11 in the center thereof arranged parallel with the longitudinal side edges. Protruding from one of the longitudinal sides of the stamping and in a same plane with the surface there-

of, are spaced lugs 12 which are spaced the same distance apart as the slots 11 and are of the same width as the slots 11. Each of the lugs 12 has a V-shaped cut-out portion 13 forming two spaced tapered fingers 14.

5 The stamping 10 can be formed by any suitable means such as stamping from sheet stock or, in a case of softer metals such as gold, silver or platinum, can be formed by hand.

The stamping is subjected to a further operation designed to shape it, as shown in Fig. 3. Each longitudinal half 15 of the stamping on either side of the slots 11 is shaped to form a concave trough 16 which, on the reverse side, presents the appearance of a semi-cylinder. The 15 troughs 16 are so formed that a narrow rectangular portion 17 of the stamping, which includes the slots 11, remains in its original flattened position; the troughs 16 retain integral end portions 18, whereby a link blank 19 is 20 provided.

Each individually shaped blank forms a separate link of the chain of the present invention and, as will readily be seen from the manner of assembly hereinafter to be described, no separate 25 connecting links are necessary.

As best shown in Fig. 4, the lugs 14 of one link are slipped into the slots 11 of the next link from the cylindrical side of the blank, and the spaced arms 14 on the lugs are then spread outwardly. Since the lugs were originally of the same width as the length of the slots 11, the outward spread of the arms 14 prevents removal of the lugs and securely joins the two links of the chain together.

35 The blank 19 into which the lugs of the preceding blank 19 were inserted, is now bent in half, trough to trough, as shown in Fig. 5, to complete the link 9. The outer surface of the link 9 now presents a cylindrical appearance with 40 closed ends formed by the end sections 17. The lugs 14 on each succeeding blank 19 can now be inserted in a similar manner in the end link of the chain assembly and the operation repeated until the chain is of any desired length. 45

It is thus evident that the chain of the present invention is easy and economical to manufacture, that its parts are readily assembled, that the final product is admirably adapted for its intended purpose and will present a pleasing 50 appearance to the eye, and that the novel chain readily lends itself to both manual or machine assembly.

It can also be readily seen that the described and claimed construction eliminates the use of 55

a separate connecting link without impairing the strength and flexibility of the final product. The factory costs are also lowered inasmuch as the manufacture of a separate connecting link is eliminated and the step of adding a separate connecting link during the assembly is also eliminated.

5. While a specific form of link has been described herein, this specific form is merely illustrative and I do not wish to be limited thereby, as it is obvious that the material, shape, size, form and ornamentation of the links can be changed to meet the requirements for different chain designs without departing from the spirit and scope 10 of the invention as described in the specification and as defined in the claims appended hereto.

I claim:

1. A stamping for forming a metallic link comprising a body portion formed of flat sheet stock, 20 said body portion having two spaced longitudinally aligned slots located midway between the longitudinal edges of said body portion and two spaced laterally extending lugs integral with one of the longitudinal edges of said body portion, the spacing of said lugs being equal to the spacing 25 of said slots.

2. An ornamental blank adapted to be incorporated into a flexible metallic chain, comprising an ornamental body portion having spaced

parallel complementary portions each forming half of a hollow tube and integrally joined by an elongated portion having a slot, one longitudinal edge of said body portion having an integral laterally extending lug, said lug being of 5 equal width to the length of said slot.

3. An ornamental blank adapted to be incorporated into a flexible metallic chain, comprising an ornamental body portion having spaced 10 parallel complementary portions each forming half of a hollow tube and integrally joined by an elongated portion having spaced slots, one longitudinal edge of said body portion having integral laterally extending spaced lugs, the spacing on said lugs being complementary to the spacing 15 on said slots.

4. The method of forming an ornamental metallic flexible chain having no separate connecting links and comprised of links each having ornamental portions, an integral connector, and a 20 connector retainer portion, including the steps of inserting the connector of one link into the retaining portion of the adjacent link, displacing the ends of said connector to prevent withdrawal from said retaining portion, and folding the ornamental portions over the displaced connector and the retaining portion to completely conceal the engaged parts. 25

WILLIAM F. HESS.
